UNITED STATES PATENT OFFICE.

ANTON BASKY, OF NEW YORK, N. Y.

POINTING MACHINE.

Application filed November 10, 1922, Serial No. 600,175. Renewed June 4, 1924.

To all whom it may concern:

Be it known that I, ANTON BASKY, a citizen of the United States, residing at New York, in the county of New York and State 5 of New York, have invented certain new and useful Improvements in Pointing Machines, of which the following is a specification.

This invention relates to a machine for 10 the use of stone, marble and wood carvers generally or sculptors and clay modelers, by means of which an exact copy, on a different scale, can be made from a model.

The invention has for an object the provision 15 of a novel and efficient machine of this sort, a further object relating specifically to the provision of means for varying the distance between the pointers, or other implements, bearing respectively on the 20 model and on the work.

For further comprehension of the invention, and of the objects and advantages thereof, reference will be had to the following description and accompanying drawings, and to the appended claims in which the various novel features of the invention 25 are more particularly set forth.

Fig. 1 of the drawings is a side elevation of my improved pointing machine.

30 Fig. 2 is a plan view, omitting the supports.

Fig. 3 is a detail transverse sectional view taken on the line 3—3 of Fig. 2.

Fig. 4 is a detail transverse sectional view 35 taken on the line 4—4 of Fig. 2.

Fig. 5 is a detail elevational view indicating a motor actuated drill which I may employ in connection with my improved machine.

40 Fig. 6 is a detail transverse elevational view illustrating the device I may employ to engage the top of model and work to hold the same steady.

In constructing my improved machine I 45 provide a pair of turntables 10 and 11 respectively the former of which is comparatively small and supported on a relatively high stand 12, and is adapted to support a model M from which a larger image is to 50 be reproduced. The turntable 11 is comparatively large and is supported on a relatively low stand 13 this table supporting the object or work W being produced.

These turntables 10 and 11 are fixed on the upper ends of vertical shafts 15 and 16 55 respectively, which are journaled in the respective stands 12 and 13. These shafts are formed with double crank elements 17 joined by connecting rods 18 whereby the two turntables may be caused to rotate in 60 unison. Anti-friction bearings 19 may be used to support the turntable 10, while rollers 20 may be placed under the edge of the turntable 11.

Located beyond the small turntable 10, 65 considered with relation to the large turntable 11, is a hollow post 23 suitably fixed to the floor and which is adapted to support the working beam of the machine, the post being located in horizontal alinement with 70 the two turntables.

The working beam, on which are mounted the pointers or other implements adapted to engage the model and work, is indicated 75 at 25 and is here of hollow construction and rectangular cross section and is divided into two compartments by a longitudinal partition, the top presenting a pair of longitudinal slots 27 one on each side of this 80 partition. In the respective compartments thus formed are slidably located the bars 28 and 29 to which are fixed brackets 30 projecting through the slots 27 and having fixed 85 thereon the horizontal disks 31. Rotatively mounted on these disks 31 are other disks 32, 32' upon which are adjustably secured as by screws 33 the transverse arms 34 and 35 respectively, carrying at one end projecting pointers 36, 37 adjustably held by set screws 38. The opposite ends of these 90 arms 34, 35 are connected together by a telescopic link consisting of two sections 40, 41 one of which fits in the other and is locked in adjusted position by a set screw 42.

In working on certain objects it may be desirable to vary the distance between the pointers while maintaining their proportionate distances from the fulcrum stand 23. To effect this a lever arm 44 is pivoted at 100 one end as at 45 to the working beam 25 and has attached thereto, at different distances from its pivot point, a pair of links 46, 47 which are connected at opposite ends to the bars 28 and 29 respectively. These 105 links are so arranged that when the lever 44

is swung the bars 28, 29 will be moved relative distances which will maintain the proper proportionate spacing of the pointers 36, 37.

5 The working beam 25 is supported on the post 23 by a universal joint and is also adapted for raising or lowering. As here shown the post is hollow and has slidably and rotatably fitted therein a rod 50 on 10 whose upper end is a vertical ring 51 freely surrounding an inner ring 52 which latter is flanged over the sides of the outer ring to prevent axial displacement. The beam 25 extends through this ring 52 and is pivotally attached thereto as at 53. Rotatively mounted on the top of the post 23 is a collar 54 through which the rod 50 passes freely, a set screw 55 being threaded through this collar and bearing on the rod to hold the 15 latter in vertically adjusted positions. Anti-friction bearings 56 may be interposed under the collar 54 while similar anti-friction bearings (not shown) may be provided between the rings 51 and 52. A counterbalancing weight 57 may be mounted on the beam 25.

In Fig. 5 I have shown a motor driven drill which may be substituted for the pointer to act upon the work. According 30 to this construction a disk 34^a may be substituted for the disk 32'. On this disk 34^a a motor 58 is mounted and the shaft 59 thereof is provided with a chuck 60 adapted to hold the drill 61, the disk 34^a having an 35 integral arm extension 62 to which the telescopic rod 40 is connected. The motor 58 may be either an electric or pneumatic motor as desired.

It is believed that the manner of use of my 40 improved pointing machine will be readily understood from the above description. As will be apparent, the working beam may be readily reversed by rotation on its own axis so as to project the pointers to right or left 45 as may be desired to engage either front or back of the model and work, while the lever 44 may be swung to move the pointer along the work beam. In order to facilitate setting the pointers in parallel relation after 50 swinging lever 44 the disks 32, 32' may have marks 70 thereon with which the arms 34, 35 are brought into registry.

I may attach a supporting cord 70 to the beam 25, at a point between the disks 32 55 and 32'. This cord leads upwardly around pulleys 71 on a horizontally swinging bracket 72 fulcrumed as at 72' in vertical alinement with the stand 23, the cord being attached to a counterweight 73 suitably 60 guided for vertical movement by said bracket.

To engage the head of model and work to steady the same I may fix to the sides of the turntables 10 and 11 the posts 76, 77 65 having fixed horizontal arms 78, 79 on their

upper ends which are pivotally engaged as at 80 with fixed elements carried overhead, the pivot points of the arms being alined with the shafts 15, 16. Upon the respective posts are vertically slidable other horizontal arms 81, 82 clamped thereto by set screws 83 and carrying pointers 84 vertically alined with said shafts and adapted to engage the heads of the model and work. 70

Having thus described my invention what 75 I claim as new and desire to protect by Letters Patent of the United States is as follows:

1. A machine of the type set forth comprising a pair of turntables vertical cranked 80 shafts on which said turntables are mounted, connecting rods extending between said shafts whereby the latter may be caused to rotate in unison a work beam, a universal joint mounting for said work beam, a pair 85 of pointers mounted on said work beam, and means for adjusting said pointers in unison along the work beam while maintaining their proportionate distances from the fulcrum point of the latter. 90

2. A machine of the type set forth comprising a pair of turntables, a post horizontally alined with said turntables, a work beam fulcrumed on said post, a pair of 95 pointers mounted on said work beam and means for adjusting said pointers in unison along the work beam while maintaining their proportionate distances from the fulcrum point of the latter.

3. A machine of the type set forth comprising a pair of turntables, a post horizontally alined with said turntables, a work beam fulcrumed on said post, a pair of 100 pointers mounted on said work beam and means for adjusting said pointers in unison along the work beam while maintaining their proportionate distances from the fulcrum point of the latter, said means comprising a pair of bars slidable in said work beam, a lever fulcrumed to said work beam, and a pair of links connected at one end to 105 said lever at relatively different distances from its fulcrum point and at opposite ends to said bars. 110

4. A machine of the type set forth comprising a pair of turntables, a post horizontally alined with said turntables, a hollow work beam supported on said post by a universal joint, a pair of bars slidable in said 120 work beam, disks rotatable on adjacent ends of the respective bars, pointers carried by said disks, a lever fulcrumed to said work beam, and links connecting said lever to said bars. 115

5. A machine of the type set forth comprising a pair of turntables, a post horizontally alined with said turntables, a work beam fulcrumed on said post, a pair of 125 pointers mounted on said work beam and means for adjusting said pointers in unison 130

along the work beam while maintaining their proportionate distances from the fulcrum point of the latter, said means comprising a pair of bars slideable in said work beam, a lever fulcrumed to said work beam, and a pair of links connected at one end to said lever at relatively different distances from its fulcrum point and at opposite ends to said bars, and means for securing said work beam in vertically varied positions on said post.

In testimony whereof I have affixed my signature.

ANTON BASKY.
